UNITED STATES PATENT OFFICE.

JESSE A. B. SMITH, OF STAMFORD, CONNECTICUT, ASSIGNOR TO UNDERWOOD ELLIOTT FISHER COMPANY, OF NEW YORK, N. Y., A CORPORATION OF DELAWARE.

COPYHOLDER FOR TYPEWRITING MACHINES.

Application filed November 8, 1924. Serial No. 748,554.

This invention relates to copy-holder attachments for typewriters in which a copy-sheet is fed line by line past a guiding plate.

In the drawings, this invention is illustrated in connection with an Underwood combined typewriting and computing machine having a fan-fold attachment, such as that disclosed in the application of William F. Helmond, Serial No. 609,560, filed December 10, 29, 1922.

The copy-holder is mounted considerably higher than the machine, straddling the same and the fan-fold attachment, and is so placed that the operator may at all times have the line of copy being read in the same position and directly in the normal line of vision.

The copy-sheet is inserted around the copy-carrying cylinder and is run down a paper-chute at the introductory side and fed around the under side of the cylinder by means of co-operating pressure rolls, and up in front of the cylinder to a position where the first line of copy will be visible to the operator past the aligning edge of a guiding plate at the delivery side of the cylinder. The cylinder is manually operable by means of a finger-wheel in one of its ends fastened to the shaft which carries the cylinder.

Successive lines on the copy-sheet are made visible by feeding the same around the cylinder one line at a time as the lines of writing are read, and, in order to facilitate the feeding of the copy-sheet, another finger-wheel is provided near the key-board of the machine, and is operatively connected to the cylinder by means of a suitable transmission comprising a rearwardly-extending shaft connected by means of bevel-gears to an upwardly-extending shaft which is in turn operatively connected by means of meshing bevel-gears to the copy-cylinder.

In order that the copy-holder may be removed and new carbon-sheets may be placed in the carbon-carrying frame of the fan-fold attachment, or, for any other reason, the copy-holder may be removed from the supporting brackets by loosening the binding screws provided for fastening the copy-holder to said supporting brackets. The removable unit comprises a yoke-piece joining together the two end frames in which the cylinder is journaled, a paper-chute forming an aligning edge at the delivery side of the cyl-

inder, and the pressure-rolls resiliently fastened to said paper-chute.

Other features and advantages will hereinafter appear.

In the accompanying drawings,

Figure 1 is a side view in elevation, showing the copy-holder as applied to a combined typewriting and computing machine having a fan-fold attachment.

Figure 2 is a cross-sectional view on the line 2—2 of Figure 3, looking in the direction of the arrows.

Figure 3 is a front view in elevation, showing the copy-holder straddling the machine, and the fan-fold attachment therefor.

Referring more particularly to Figure 1 of the drawings, 10 is a typewriter mounted upon a computing machine 11 and supported by a stand 12. To the rear of the typewriter there is shown a fan-fold attachment, including supporting brackets 13, a carbon-carrier 14 and a handle 15 for operating the latter.

A copy-sheet 16 is inserted around a copy-carrying cylinder 17, and is run down a paper-chute 18 and forwardly around the under side of the cylinder 17 and up in front thereof; the copy-sheet 16 is carried around the cylinder by pressure rolls 19 co-operating with said cylinder and is fed to a position where the first line of copy 20 is exposed past the aligning edge 21 at the delivery side of the cylinder 17, which is operable by means of a finger-wheel 22 fast on a shaft 23, which also carries the cylinder 17. The pressure rolls 19 are held under tension, and bear against the cylinder 17 by means of supporting springs 46 fastened to the paper-chute 18 by screws 47.

In order to advance the copy-sheet for line-spacing the same and for successively bringing into view new lines of writing on the copy-sheet, there is provided mechanism whereby the copy-cylinder may be operated from a conveniently-placed finger-wheel 24 near the keyboard of the typewriter. The finger-wheel 24 is fast on a rearwardly-extending shaft 25 journaled at 26 and 27, and is provided at its rearmost end with a bevel-gear 28 operatively meshing with another bevel-gear 29 fast upon a shaft 30. Said shaft 30 is journaled at 31 and 32 on a supporting bracket 33, and is operatively connected to the cylinder 17 by means of a second set of bevel-gears 34 and 35, which are re-

spectively fastened to the shafts 30 and 23, the latter carrying the cylinder 17.

Supporting the cylinder 17, there are shown in the drawings the brackets 33 and 36 fastened to the machine stand 12 by means of screws 37, said brackets being reinforced by the trusses 38 fastened to the supporting brackets 13 by screws 39 and to the brackets 33 and 36 by means of screws 40.

10 The copy-holder is designed to be detachable from the supporting brackets in order that new carbon-sheets may be placed in the carbon-carrier of the fan-fold attachment. The removable section forms a self-contained 15 unit and comprises two end plates 41 and 42 and the cylinder 17 journaled therein, the plates being joined together by a yoke-piece 43 and by the paper-chute 18 upon which the pressure rolls are mounted. The plates 41 20 and 42 are provided with slots 45 fitting over corresponding lips in the supporting brackets 33 and 36, and are held in place by means of screws 44 in the plates 41 and 42.

25 Variations may be resorted to within the scope of the invention, and portions of the improvements may be used without others.

Having thus described my invention, I claim:

30 1. The combination with a typewriting machine having a reciprocable carriage of a copy-holder, bracket supports therefor, each support extending upwardly from below the typewriting machine with one support on either side thereof, detachable end plates on 35 the upper ends of the supports for supporting the copy-holder at either end thereof above the typewriting machine, the bracket supports being sufficiently far apart to allow reciprocation therebetween of the typewriter carriage.

40 2. The combination of a copy-holder, bracket supports therefor, each support terminating in a lip, end plates at either end of the copy-holder, said end plates each having a slot therein into which the lips of the supports may extend to hold the copy-holder in 45 position and to permit it to be lifted from the supports.

50 3. The combination of a typewriter stand, a copy-holder comprising end plates, a revolvable cylinder journaled in the end plates, a paper chute attached directly to the end plates for joining them together, the paper

chute extending around the under side of the cylinder and terminating at the delivery side of said cylinder with the straight edge parallel to the axis of the cylinder, a plurality of pressure rolls resiliently mounted upon said paper chute and cooperating with said cylinder for feeding a copy sheet therethrough, and means for supporting said copy-holder including a supporting member on either side of the top of the stand. 55

4. The combination of a typewriter stand, a copy holder comprising end plates, a revolvable cylinder journaled in the end plates and 60 having a paper chute attached directly to the end plates for joining them together, the paper chute extending around the under side of the cylinder and terminating at the delivery side of said cylinder with the straight edge parallel to the axis of the cylinder, a plurality of pressure rolls resiliently mounted upon said paper chute and cooperating with 65 said cylinder for feeding a copy sheet therethrough, and means for supporting said copy-holder including a supporting member on either side of the top of the stand. 70

75 5. A copy-holder having a gear wheel at one end, brackets for supporting said copy-holder but readily detachable therefrom, a chain of operating mechanisms intergeared with said gear wheel and extending downwardly therefrom and to the front for operating the copy-holder said chain of mechanisms being broken by detaching the copy-holder from the brackets. 80

90 6. A copy-holder having end plates, a gear wheel at one end of the copy-holder, brackets for supporting said end plates and having slotted connections therewith whereby the copy-holder may be readily detached from the brackets, a chain of operating mechanisms intergeared with said gear wheel and extending downwardly and to the front for operating the copy-holder, said chain of mechanisms 95 being broken by detaching the end plates from the brackets. 100

JESSE A. B. SMITH.
